CLAIM

The ornamental design for a display screen with a graphical user interface, as shown and described.

DESCRIPTION

The FIGURE is a front view of a display screen showing a display screen with a graphical user interface embodying our new design.

The broken lines in the FIGURE illustrate portions of the display screen with a graphical user interface that form no part of the claimed design.

The dash-dot broken line showing of a display screen forms no part of the claimed design.

1 Claim, 1 Drawing Sheet
